AIR MOTOR

Filed Sept. 19, 1921

Phillip H. Packel
INVENTOR.

BY
Geo. B. Wilcox ATTORNEY

UNITED STATES PATENT OFFICE.

PHILLIP K. RUCKEL, OF SAGINAW, MICHIGAN.

AIR MOTOR.

Application filed September 19, 1921. Serial No. 501,523.

To all whom it may concern:

Be it known that I, PHILLIP K. RUCKEL, a citizen of the United States, residing at Saginaw, in the county of Saginaw and 5 State of Michigan, have invented certain new and useful Improvements in Air Motors; and I do hereby declare the following to be a full, clear, and exact description of the invention, such as will enable others 10 skilled in the art to which it appertains to make and use the same.

This invention relates to air motors and pertains more particularly to an improved construction of air motor or wind mill.

15 The improvement pertains more specifically to a novel combination and arrangement of vanes and the mechanism for automatically adjusting the vanes to different planes during their revolution about the 20 axis of the wheels upon which the vanes are mounted.

25 The general construction and mode of operation of my improved wind wheel is illustrated and described in my copending application, Serial No. 459,600, in which the vanes and their actuating mechanism are described as being adapted to propulsion of an aeroplane. Reference may be had to the 30 above-mentioned application for detail description of the construction and mounting of the blades on the revolving wheels.

35 My present invention provides a strong, yet comparatively simple air motor construction whereby a greater degree of air pressure may be obtained per square foot of wind plane or vane surface, and whereby high speed of revolution of the main shaft of the air motor may be attained.

40 With these and certain other objects in view, which will appear later in the specification, my invention comprises the devices described and claimed and the equivalents thereof.

45 In the drawings, Fig. 1 is a front elevation of a wind mill or air motor embodying my improvement.

Fig. 2 is a side view, broken away in part, of one of the power wheels and its mounting.

50 Fig. 3 is an enlarged fragmentary sectional view, taken on the line 3—3 of Fig. 4.

Fig. 4 is a diagrammatic side view of the wheel rim upon which the vanes are piv-

otally mounted and of the cam track by which the angular positions of the vanes 55 are automatically changed during the revolution of the vanes.

Figs. 5 and 6 are respectively a plan view and an edge view of one of the roller-carrying bars that co-act with the cam track to 60 properly shift the radial positions of each of the feathering blades as they revolve.

Referring to Fig. 1, the air motor comprises the usual tower or frame 1, upon the top of which is carried an annular ball race 2 which is capped by a revolvable plate 3 formed with a ball race on its under side. Between the two ball races are received the 65 balls 4, upon which the plate 3 revolves.

Plate 3 carries a pair of standards 5, 5, 70 in which is mounted the tail shaft 6 of tail 7. Disposed at right angles to the shaft 6 and mounted on the plate 3 is a pair of brackets 8, 8, having bearings 9, 9, in which the main shaft 10 is revolvably mounted. 75

Fixed to the main shaft 10 near its center is a bevel pinion 11, or its equivalent, meshing with a bevel pinion 12, which is fixed to the upper end of the downwardly projecting shaft 13. This shaft projects through a vertical bearing 14 formed by the hubs of plates 2 and 3. In Fig. 2 shaft 13 is removed from the bearing for the sake of clearness.

80 Each of the bearings 9 is preferably formed with an integral projecting boss 15—see Fig. 3—and rigidly fixed to this boss is a plurality of spokes 16 supporting a cam track or rim 17 of irregular curved shape, as shown in Figs. 2 and 4, and of substantially U-shaped cross section, as shown in Fig. 3.

85 Keyed to the shaft 10 near hub 15 is a wheel hub 18, to which is fixed a plurality of spokes 19 carrying a wheel rim 20. 95

The hub 18, spokes 19 and rim 20 form in effect a wheel keyed to the shaft 10 as an axle. There are preferably four such wheels mounted on the shaft 10, two on each radially projecting end of the shaft, as shown 100 in Fig. 1.

105 Between the wheels of each pair is a plurality of wind vanes or wings 21, each carried by a revolvable shaft 22 having its ends journaled in the rims of wheels 20, so that each vane 21 is tiltably mounted on the pair

of wheels 20, and each vane revolves with the wheels and with the shaft 10.

Referring now to Fig. 2, it will be seen that with the wind traveling in the direction of the arrow it will encounter the practically vertical surfaces of the two topmost vanes. As the wheel revolves, the vanes travel downwardly and then forwardly. Each vane in its forward travel is moving against the wind, but in a horizontal position, substantially edgewise to the wind. The change in angular position of the vane from the vertical position shown at the top in Fig. 2 to the horizontal position shown at the bottom, is effected by means of the fixed cam track 17 located alongside the wheel 20. The shape of this cam and the means by which the cam is connected to the vane are such that the proper angular movement and reversal of the direction of the vane is attained during each revolution of the wheels.

Upon the end of central shaft 22 of each tiltable vane is secured a radially projecting bar 23 having idler rollers or equivalent projections 24 and 25 journaled at its ends. When the bar 23 of one of the propelling vanes has one of its end rollers, as 25, traveling in the cam track 17, the radial or angular position of the bar 23, and consequently of the vane to which the bar is attached, will be determined by the relative position and direction of curvature of the cam track 17 with respect to the axis of the vane. The arm 23 and its rollers 24 and 25 form the operating connection between the tiltable vanes 21 and the cam track 17. The vanes take the successive positions indicated by the dotted lines in Fig. 4.

It will be noticed in Fig. 4 that the outer radial edge of any given plane is, when vertical, outside the boundary of the cam 17 and remains outside during the rearward, downward and part of the forward movement of the vane, but during the upward movement of the vane, this edge is inside the boundary of the cam 17. To make this shift in the position of the vane while it revolves, I prefer to arrange the cam track 17 as shown in Figs. 2 and 4, where the rollers 24 and 25 travel as indicated diagrammatically by the dotted lines.

In the lower left-hand part of Fig. 4, roller 24 is shown as just entering one open end of the cam track 17 while the opposite roller is leaving the intersecting exit end 26 of the cam. During the next succeeding revolution of the vane, roller 24 travels around the length of the cam and as it leaves the exit end 26 of the cam, roller 25 will then be entering, so that at each revolution of the wheels about the cam the position of the vane is reversed.

During one revolution roller 25 of arm 23 travels around the cam and during the

next succeeding revolution the opposite roller 24 travels around the cam.

To avoid accidental crowding of the rollers 24 and 25 in the upper part of cam track 17 where the direction of inclination of the wind vanes 21 is changed as indicated in Fig. 4, and to insure such change of inclination occurring smoothly even when running at high speeds, I provide on bar 23 a fixed deflecting wiper or guide 27 adapted to engage a fixed cam 28 which may be secured by means of spokes to cam track 17, as shown in Fig. 2.

By this means I avoid any abrupt change of the angle of tilt as the vanes pass around the upper area of their travel, and without interfering with the normal action of cam track 17 and idler rolls 25 I thereby insure a gradual and positive change of tilt of the vanes.

The tail 7 keeps the vanes headed into the wind as in an ordinary wind mill, and by mounting a power wheel at each side of the vertical axis, as shown in Fig. 1, the parts are balanced so that the tail 7 turns the mechanism in a horizontal plane with the greatest ease.

During the working part of the revolution, it will be seen that the propelling vanes are practically at right angles to the direction of the wind and that each vane as it travels back before the wind gradually tilts and presents its surface at a slight angle to the wind, as shown at the left in Fig. 2, so that the blast of air strikes the vane surface in the same manner that the air strikes the sail of a boat running athwart the wind.

As is well known, under these conditions a very high speed of rotation can be attained. During the return or forward travel of the vane, it is presented practically edgewise to the wind, offering the least possible surface resistance and as it rises to its working position for the return stroke the vane is again so presented to the wind that the tendency of the wind is to further increase the propelling power. Thus during each revolution of a vane I avail myself not only of the propelling power while the vane is at right angles to the wind, but I also turn the vane at the beginning and end of each working movement in such relation to the wind that the vane adds materially to the propelling power on its normal working travel.

While I have shown and described in Fig. 4, the angle of the vanes as changing from horizontal at the bottom of the circle of travel, to vertical at the top, and making the change very gradually during the upward movement of the vanes, it is obvious that by slightly altering the shape of the cam 17, the blades may be made to change their inclination more or less rapidly, so as

to bring them to their vertical position earlier or later on the working arc of the circle, as desired.

Having thus described my invention, what I claim and desire to secure by Letters Patent is:

1. In an air motor, the combination of a revolvable support, a tail carried by said support, a shaft rotatably mounted on said support and projecting radially therefrom, a pair of wheels fixed to each of the projecting ends of said shaft, the wheels of each pair spaced apart, a plurality of tilttable vanes mounted between the rims of said wheels, a radially projecting bar and a deflecting wiper secured to said vane, projections on the ends of said bar, a cam track of approximately circular shape throughout the length of its circumference and located in fixed position relative to said vanes, a fixed cam guide in the path of travel of said wiper, the projections on said bar movably engaged with and adapted to travel along said cam track.
2. In an air motor, the combination of a support revolvable in a horizontal plane, a tail carried by said support, a main shaft rotatably mounted on said support and projecting radially therefrom, a pair of wheels fixed to each of the projecting ends of said main shaft, the wheels of each pair spaced apart, a plurality of shafts mounted be-

tween the rims of said wheels, a radially projecting bar secured to each of said shafts, rollers on the ends of said bar, tilttable vanes secured to said shafts, a cam track of approximately circular shape throughout the length of its circumference and located in fixed position relative to said vanes, a fixed cam guide and a wiper on said vane, the rollers on said bar movably engaged with and adapted to travel along said cam track.

3. In an air motor, the combination of a revolvable support, a tail carried by said support, a shaft rotatably mounted on said support and projecting at each side radially therefrom, a pair of wheels fixed to each of the projecting ends of said shaft, the wheels of each pair spaced apart, a plurality of tilttable vanes mounted between the rims of said wheels, a radially projecting bar secured to said vane, rollers on the ends of said bar, a cam track of irregular curved shape located in fixed position relative to said vanes, said cam track having two open ends comprising intersecting guideways, a fixed cam guide and an angularly disposed wiper on said vane, the rollers on said bar movably engaged with and adapted to travel along said cam track.

In testimony whereof I affix my signature.

PHILLIP K. RUCKEL.
